ATTORNEY

UNITED STATES PATENT OFFICE

WALTER VAN B. ROBERTS, OF PRINCETON, NEW JERSEY, ASSIGNOR TO RADIO CORPORATION OF AMERICA, A CORPORATION OF DELAWARE

NEUTRALIZING CIRCUIT

Application filed September 3, 1927. Serial No. 217,368.

My invention relates to a neutralizing circuit and more particularly it relates to improvements on the neutralizing circuit disclosed by C. W. Rice in the United States 5 patent granted to him on March 16, 1920, No. 1,334,118.

By neutralization, it has been attempted in various radio receiving circuits to prevent two effects, first, radiation by an antenna 10 caused by an impulse in an output circuit feeding back energy to an input circuit which in turn is coupled to the antenna, and secondly, to prevent regeneration which causes (sometimes) sustained local generation of 15 oscillations. Of the two effects, only regeneration produces a distorting effect in a receiver.

In bridge neutralizing circuits known at 20 present, blocking action, (that is, perfect prevention of radiation) is maintained where a divided input circuit and a neutralizing condenser is used in connection with a thermionic amplifier. However, for the reason that it is impossible to obtain 100% coupling in 25 the inductances of the divided input circuit, an absolute zero of regenerative action independent of frequency and tuning has not been obtained.

Consequently, it is an object of this invention 30 to provide a neutralizing circuit in which regenerative distortion is completely absent and in which this adjustment is maintained perfect at the expense of the radiation blocking, in such a manner that, even though radiation blocking is not 100% efficient in my system, radiation will be kept so small that it will not seriously affect nearby receivers. Therefore it can in effect be said 35 that this invention provides a neutralizing system in which regenerative action is completely eliminated and in which radiation blocking is approximated.

Another object of this invention is to provide 40 a neutralizing system in which the neutralizing means are kept constant, that is, to provide a neutralizing system in which regardless of the frequency to which the receiver is tuned, it will not be necessary to 45 vary the value of the neutralizing means in

order to maintain complete absence of regenerative effects at the signal frequency.

The manner in which these objects will be carried out will be explained below with the aid of the accompanying drawing in which 55

Fig. 1 is a wiring diagram of my improved neutralizing circuit;

Fig. 2 shows Fig. 1 redrawn as a bridge, and

Fig. 3 shows my improved circuit coupled 60 to a receiving antenna.

Referring to Fig. 1, C_5 , L_1 and L_2 indicate a tuned divided input circuit. Voltage variations across part of the tuned circuit indicated by L_1 are applied across the grid and filament of the thermionic tube indicated diagrammatically in Fig. 1, the filament, grid and plate of which are denoted by the numerals 1, 2 and 3 respectively. 65

Regeneration in this type of circuit may 70 be explained as follows. When an input voltage is applied across the grid 2 and filament 1 of the tube, a plate voltage appears as a voltage drop across the load in the plate circuit. This voltage tends to force a capacity current i_3 from plate 3 to grid 2 of the tube. Some of this capacity current i_3 will 75 flow through L_1 as indicated, the portion of the current flowing through L_1 being indicated by the numeral i_1 . As a result, the 80 current i_1 will cause a drop in voltage between the grid 2 and filament 1 of a value equal to $i_1 Z_1$ where Z_1 represents the reactance of L_1 thus giving rise to what is 85 known as the undesired regenerative action which causes distorting effects in the receiver telephone.

In order to prevent the regenerative and radiation effects, it has been proposed to 90 form a bridge such as shown in Fig. 2 in which the coupling between the inductance L_1 and the inductance L_2 should be 100%. Theoretically, this would accomplish both 95 results. The magnetic fields through L_2 and L_1 would completely cancel, with the result that no difference of potential between grid and filament would be produced by the presence of a plate voltage, and no current would be produced in an antenna coupled to the input circuit. Thus, regeneration would 100

be eliminated and blocking action perfected both at once.

But in practice, it is impossible to get 100% coupling between inductances L_1 and L_2 . In case the bridge is balanced this will be immaterial as far as radiation blocking is concerned, since as shown in Fig. 2 if a small current flows in L_1 and L_2 due to the voltage e , the voltage drops in L_1 and L_2 will be equal, the grid 2 and point A will be at the same potential and therefore there will be no feed-back from the output to its conjugate input circuit if properly coupled to the two coils.

According to my invention, however, the bridge is deliberately unbalanced, thus impairing the perfection of blocking action, but securing in its stead complete absence of regeneration action, and in order to secure this result I make the capacities C_5 and C_4 constant, and I make the coupling between inductances L_1 and L_2 zero, by separating them and by keeping them at right angles, and I make the ratio of inductance L_1 to inductance L_2 equal to K , a constant.

The results of these changes made according to my invention may best be explained mathematically, particular reference being had to Fig. 1 which indicates the various currents flowing in the various capacities and inductances of the circuit.

Starting with the general case where there is mutual inductance L_m between L_1 and L_2 , indicating the various impedances by Z with an appropriate sub-numeral and applying Kirchoff's laws to the various meshes we have,

$$\begin{aligned} (1.) \quad & i_4 Z_4 + i_2 Z_2 - i_1 Z_m = e \\ (2.) \quad & i_3 Z_3 + i_1 Z_1 - i_2 Z_m = e \\ (3.) \quad & i_4 Z_4 + i_5 Z_5 - i_3 Z_3 = 0 \\ (4.) \quad & i_4 = i_2 + i_5 \\ (5.) \quad & i_1 = i_3 + i_5 \end{aligned}$$

For zero regeneration, there must be no potential difference between grid and filament when the plate altering electro-motive force e is present. That is, going from point Q to point Y to point H the alternating electro-motive forces must add up to zero and therefore for zero regeneration

$$(6.) \quad i_3 Z_3 = e$$

Under these conditions solving the six equations given above it will be found that for zero regeneration

$$(7.) \quad Z_4 = \frac{Z_3 Z_5 Z_m - (Z_3 + Z_5)(Z_1 Z_2 - Z_m^2)}{Z_1 Z_5 + Z_1 Z_2 - Z_m^2}$$

Equation (7) then, by inversion and division by a constant, (since the various impedances are in effect reactances) gives the value which the neutralizing condenser C_4 must have at the frequency to which the input circuit is tuned in order to have zero regeneration. Equation (7) also gives the

value of the neutralizing capacity necessary for zero regeneration when there is mutual inductance between the coils L_1 and L_2 .

However, remembering that

$$X_C = \frac{1}{2\pi f C} \text{ and } X_L = 2\pi f L$$

it will be clear that at each frequency to which the input circuit is tuned, for zero regeneration, a new value of neutralizing capacity C_4 may be required. But if according to my invention the coupling between L_1 and L_2 is made equal to zero, the value of the neutralizing reactance for zero regeneration becomes

$$(8.) \quad Z_4 = (Z_3 + Z_5) - \frac{Z_2}{Z_2 + Z_5}$$

which again shows that the value of the neutralizing capacity for zero regeneration when the coupling is zero is again not independent of the frequency.

If however, we consider the frequency to which the circuit is tuned and for which

$$(9.) \quad Z_1 + Z_2 = -Z_5, \text{ approximately}$$

and if, according to my invention, in addition to making the mutual inductance between L_1 and L_2 equal to zero, we make

$$(10.) \quad \frac{L_2}{L_1} = K = \text{a constant}$$

then Equation (8) becomes

$$(11.) \quad Z_4 = (Z_3 + Z_5) K$$

Equation (11) shows that the value of the neutralizing capacity for zero regeneration at the tuned frequency is a constant provided that capacities C_3 and C_5 are kept constant, and provided that the inductance ratio K remains constant. Having done this, it can be said that my arrangement of the Rice circuit with no mutual inductance between the inductances, indicated in Fig. 1 by L_1 and L_2 , may have zero regeneration at the frequency to which the input circuit is tuned, and the neutralizing capacity which gives this result is the same regardless of the frequency to which the input circuit may be tuned.

Altho by my system the capacity C_5 must remain constant, the input circuit may be tuned by varying the inductances L_1 and L_2 , while maintaining their ratio constant.

The manner in which the zero mutual and the constant ratio of inductance between the inductances L_1 and L_2 is maintained is shown in Fig. 3. Zero coupling is maintained by keeping the coils L_1 and L_2 far apart or shielded or by keeping them at right angles to one another. The inductance ratio is maintained constant by means of a suitable coupling connector 10 which varies both inductances alike and at the same time varies the natural frequency of the input circuit.

Having thus described my invention what I claim is:

1. A neutralizing bridge circuit for a thermionic tube amplifier comprising a constant capacity in one of the arms of the bridge and between the anode and cathode of the tube, and inductances in other arms of the bridge and in the input circuit of the tube having zero coupling between them whereby regenerative blocking is maintained perfect at all frequencies of oscillations impressed upon the input circuit of the amplifier.

2. A neutralizing bridge circuit comprising conjugate input and output circuits constant capacities and variable inductances in the arms of the bridge, the inductances having zero mutual inductive coupling between them, and a constant capacity in the input conjugate circuit.

3. In a circuit for the amplification of high frequency oscillations a thermionic tube, a tunable divided input circuit comprising a constant capacity and a pair of inductances whose inductance ratio for all tunings of the input circuit is maintained substantially constant and having zero coupling between them, and a substantially constant neutralizing capacity connected, between one end of one of the input inductances and the anode of the tube.

4. In a neutralizing bridge circuit utilizing a pair of capacities of constant value in the arms of the bridge, and a divided input circuit, having a capacity of constant value and a pair of inductances having zero mutual inductance, the method of tuning by varying the inductance of the divided input circuit, and simultaneously maintaining the ratio of the inductances in each branch of the divided input circuit constant.

5. A neutralizing bridge circuit for a thermionic tube amplifier comprising a constant capacity in one of the arms of the bridge and between the cathode and anode of the tube, inductances in other arms of the bridge and in the input circuit of said tube having zero coupling between them, and a capacity of constant value in shunt with said inductances.

6. A neutralizing bridge circuit for a thermionic tube amplifier comprising a constant capacity in one of the arms of the bridge and between the anode and cathode of the tube, inductances in other arms of the bridge and in the input circuit of the tube having zero coupling between them, and means for varying said inductances and simultaneously maintaining the ratio between said inductances constant at all frequencies.

7. A combination in a radio receiving system of an electron discharge amplifier having a cathode, anode and grid and having a resonant grid circuit including a pair of inductances shunted by a capacity, a connection between the cathode of said amplifier and a point between said inductances, a connection

between the anode of said amplifier and one end of one of said inductances, said inductances having zero coupling between them.

8. The combination in a radio receiving system of an electron discharge amplifier having a cathode, anode and a grid and having a resonant grid circuit comprising a pair of variable inductances shunted by a single constant capacity, a connection between the cathode of said amplifier and a point between said inductances, a connection between the grid of said amplifier and one end of one of said inductances, and means for varying the tuning of said grid circuit by adjusting said inductances, said inductances having zero mutual inductance.

9. In a neutralizing bridge circuit for a thermionic tube amplifier comprising a pair of capacities of constant value in the arms of the bridge, said amplifier having a divided input circuit comprising a capacitance of constant value and a pair of inductances having zero mutual inductance, and means for tuning the input circuit by varying the inductance of the divided input circuit.
